MARY TURNER.

UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 17,860, dated November 1, 1887.

Application filed September 21, 1887. Serial No. 250,346. Term of patent 3½ years.

To all whom it may concern:

Be it known that I, MARY TURNER, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a round walking skirt and a close-fitting basque. The skirt displays a plain panel at the left side, a flat drapery that passes across to the right side, and over which falls a wrinkled drapery that descends nearly to the edge of the flat drapery at the left side and curves high at the right side, where it exhibits draping plaits coming from the top and

from under a full puff, and a full back drapery that falls in folds even with the edge of the skirt and exhibits bournous loops at the top. The basque exhibits a narrow vest between the fronts, a tapering lapel extending all the way down the right front, underfolded plaits below the end of its middle three back seams, a standing collar, and coat-sleeves.

What I claim as my invention, and desire to secure by Letters Patent, is—

The design for a lady's costume, as shown in the engraved prints accompanying this specification.

MARY TURNER.
